BAG MACHINE AND METHOD

Francis T. Robinson, Rockville Centre, N. Y., assignor to Arkell Safety Bag Company, New York, N. Y., a corporation of New York

Application October 20, 1945, Serial No. 623,513

6 Claims. (Cl. 93—18)

1

The present invention relates to machines for and methods of manufacturing bags, and liners for bags and other containers, and has for its object to provide a novel and improved machine and method of this character.

The several features of the invention whereby this and other objects may be attained, will be readily understood from the following description and accompanying drawings, in which:

Figure 1 is a longitudinal sectional elevation, partly diagrammatical, of the machine in its preferred form;

Fig. 2 is a plan view of the same with certain parts broken away;

Fig. 3 is a sectional view, on an enlarged scale, taken substantially on the line 3—3 of Fig. 2;

Fig. 4 is a plan view of a part of the machine shown in Fig. 3;

Fig. 5 is a sectional view, on an enlarged scale, taken substantially on the line 5—5 of Fig. 2;

Fig. 6 is a detail side elevation corresponding to a portion of Fig. 1, but on an enlarged scale and with certain parts shown in different operative positions;

Fig. 7 is a rear side view partly in section of the portion of the machine shown in Fig. 6;

Fig. 8 is a sectional view, partly in elevation, taken on the line 8—8 of Fig. 6;

Fig. 9 is a detail sectional elevation, taken on the line 9—9 of Fig. 8; and

Fig. 10 is a view in perspective of a bag or liner adapted to be formed by my improved machine and in accordance with my improved method.

The machine illustrated in the drawings is particularly adapted for use in the manufacture of the bag or liner described and claimed in the pending application of James F. Doyle, Ser. No. 610,258, filed August 11, 1945, "Bag and Method" (now abandoned).

As shown, this bag or liner is made of two pieces or sheets of material 2 and 4. This material preferably comprises two sheets of crinkled paper which are separately crinkled and are laminated together by means of asphaltic or other suitable waterproof adhesive. The two pieces or sheets 2 and 4 of this laminated paper are arranged one above the other to form the side walls of the bag, the crinkles of the paper extending longitudinally of the bag. The side walls have the inner sides of their longitudinal margins 6 secured together by asphaltic or other suitable adhesive so as to form the side seams of the bag. The projecting margin 8 of the lower end of the side wall 4 is folded over the lower edge of the side wall 2 and is adhesively secured thereto by means of asphaltic or other suitable adhesive to form a closed bottom for the bag.

The upper margin 10 of the side wall 4 of the bag is folded back upon itself. The outer side of this folded margin 10 and the inner side of the adjacent margin 12 are coated with adhesive

2

11. These stripes of adhesive 11 are of such a nature that they remain tacky at normal temperatures, and when the two coated surfaces are brought together may be securely sealed by the application of heat and pressure or pressure alone so as to securely close the mouth of the bag.

Separate strips of cellophane 14 may be applied over the adhesive coatings 11 so as to protect the adhesive during shipment and storage. The edges of the cellophane strips should project slightly beyond the edges of the stripes of adhesive and the inner edges of the strips overlap so as to prevent spreading of the adhesive beyond the edges of the strip. When the bag is to be used these cellophane strips may be removed to expose the adhesive and thus permit the mouth of the bag to be closed.

Bags or liners of this type may be of considerable width, a standard width being 96 inches. In order to enable the packer to easily remove the strips 14 from the adhesive, a loop 16 is formed in each cellophane strip through which the packer may insert his finger or otherwise grasp the loop and easily rip the strip from the adhesive. In the case of the wider bags at least, the loop is preferably made in each strip substantially midway between its ends, so as to reduce the distance the strips are removed at opposite sides of the loops.

In accordance with the present invention, the side walls 2 and 4 of the bag are formed from webs 18 and 20 respectively, which are supplied to the machine in rolls 21 and 22 which are mounted to turn on shafts 24. The webs 18 and 20 are of a width corresponding to the lengths of the sheets 2 and 4, respectively. The web 20 is arranged above the web 18 and the further margin of the web 20 (viewing Figs. 1 and 2) projects a distance beyond the corresponding margin of the web 18 to provide the folded over margin 8 of the completed bags or liners. The crinkles in the webs 18 and 20 extend transversely thereof so that in the completed bag they will extend longitudinally of the bag as above described.

From the supply rolls 21 and 22 the webs 18 and 20 respectively pass over pairs of draw-rolls 26 and 28. From the draw-rolls 26 the web 18 passes beneath a guide-roll 30 and then between pressure rolls 32. The lower of these rolls is a full width roll but the upper one is narrow faced, the purpose of which is to squeeze out a little of the transverse stripe of adhesive from the upper web to the lower web so it will meet up with longitudinal stripe of adhesive when said strip is applied.

The web 20 after leaving the draw-rolls 28 passes between scoring disks 34 which score the web a distance from its edges corresponding to the widths of the margins 8 and 10 of the com-

pleted bag (Fig. 10). The web 20 then passes beneath a guide roll 36 and over a guide roll 37 to a glue-roll 38. The web 20 at this point is normally held out of contact with the glue-roll 38 by means of the guide-roll 37 and a guide-roll 40 in front of the glue roll. At predetermined points in the travel of the web, however, a wiping blade 42, secured on the ends of arms 44 which are carried by a rotating shaft 46, strikes the top surface of the web to momentarily bring the web into contact with the glue-roll 38 so as to apply stripes of adhesive to the underside thereof. These stripes of adhesive are for the purpose of securing the longitudinal margins 6 of the side walls of the completed bag together. From the guide-roll 40 the web then passes between the pressure-applying rolls 32 which cause the webs 18 and 20 to be attached together by means of the lines of adhesive applied by the glue-roll 38. A suitably supported doctor blade 39 (Figs. 3 and 4) regulates the amount of thickness of the adhesive applied by the roll 38. Also a wiper blade 41 governs the length of the stripe of adhesive according to the width of the web.

From the pressure rolls 32 the two webs thus joined pass beneath a guide-roll 48 and a narrow glue-roll 50 which applies a coating of adhesive to the under side of the projecting longitudinal margin of the web 20 which forms the folded over margins 8 at the bottoms of the completed bags.

After the two webs pass from the glue-roll 50, suitable folding blades 52 fold the near longitudinal margin of the web 20 (viewing Figs. 1 and 2) back upon itself to form the folded-over margin 10 of the completed bags. Also at this time suitable folding devices 54 fold the adhesively coated margin of the web 20 upon the underside of the corresponding margin of the web 18 to form the closed bottoms of the bags.

The webs then pass beneath a guide-roll 56 and over a guide-roll 58. As the webs pass over the guide-roll 58, a grooved glue-roll 60 applies stripes of adhesive 11 to the margins of the webs that are to form the margins 10 and 12 of the mouths of the bags.

After leaving the guide-roll 58, the webs then pass over a plate or table 61 and between draw-rolls 62. At this time, strips 63 of cellophane from supply rolls 64 are applied over the stripes of asphaltic adhesive 11, these strips forming the covering strips 14 of the completed bag. The two strips 63 are applied by means of a roller 66 over which the strips pass in overlapping relation (Figs. 6 and 7) so that when the strips are applied they are arranged in overlapping relation as shown in Fig. 10. The strips 63 are fed and guided from the supply roll 64 to the applying rolls 66, by means of a draw-roll 68 which is normally driven at the same surface speed as the webs. The rolls 66 and 68 are mounted on shafts in a bifurcated arm of a lever 70 which is secured on a rock-shaft 72. The draw-roll 68 is driven through a chain 74 which passes over a sprocket wheel secured on a shaft 69 on which the draw-roll 68 is also secured, and a sprocket wheel mounted to turn on the rock-shaft 72. The latter sprocket wheel is secured to a second sprocket wheel also mounted on the shaft 72 and driven by a chain 76 from a sprocket wheel 78 that forms one member of a one-way clutch 80, the other member of the clutch being secured on a driving shaft 82.

Secured on the hub of the sprocket wheel 78 is a ratchet wheel 84 which is engaged by a pawl 86 mounted on a pivot pin or shaft 88 carried by the

end of an arm 90 pivotally mounted on the shaft 82. This pivot pin 88 is connected by a rod or link 92 with the upper end of the lever 70.

The rock-shaft 72 is adapted to be oscillated by means of a cam arm 94 secured thereon which carries a cam roll 96 that engages a cam 98, the cam roll being held in contact with the surface of the cam by means of a coiled spring 100 connected with the cam arm 94.

With this mechanism, as the webs are being fed beneath the strip-applying roller 66, the cellophane strips 63 are uniformly applied in overlapping relation over the adhesive on the margins of the webs, the strips of cellophane being fed by the draw-roll 68 at the same surface speed as the travel of the webs.

In order to form the loops 16 in the cellophane strips at suitable intervals, the cam 98 acts through the cam arm 94, rock-shaft 72, lever 70, rod or link 92 and the pawl 86 to increase the speed of rotation of the sprocket wheel 78 with relation to its driving shaft 82, the clutch 80 permitting this to be effected. Such increase in speed of the sprocket 78 and thus the draw-rolls 68 and 66 is necessary because the draw-rolls are moving in a direction opposite to movement of the bag web, and this additional speed makes up for this rearward movement so that when arm 94 drops suddenly off the high spot of cam 98 and pulls strips 63 forward faster than the web is moving, the loops are then formed. As this occurs the lever 70 lifts the strip-applying roll 66 from the webs. When the cam 98 allows the applying-roll 66 to return to strip-applying engagement with the webs, a sufficient amount of slack has been provided in the cellophane strips to cause the loops 16 to be formed in the strips as the applying roll returns to its normal strip-applying engagement with the webs. The rod or link 92 is connected with the lever 70 through a suitable pin and slot connection 101 whereby the extent of movement imparted by the lever 70 to the ratchet wheel 78 may be varied to vary the size of the loops 16.

After the webs with the cellophane strips applied thereto leave the draw-rolls 62 they pass between a stationary cutting blade 102, and a cooperating rotating blade 104 which is operated in proper timed relation to the feeding of the webs to sever the webs on lines extending centrally through the transverse lines of adhesive which when thus severed secure together the longitudinal margins 6 of the completed bags. As the completed bags are cut off from the composite web by the blades 102 and 104 they drop upon a delivery belt 106 which discharges them from the machine.

The drive mechanism of the machine is illustrated diagrammatically and need be but briefly described. The machine may be driven from an electric motor 108 which through a belt or chain 110 drives a shaft 112. This shaft 112 carries a pinion 114 which drives a large gear 116 secured on a shaft 118 on which one of the main draw-rolls 62 is secured so as to be driven thereby. The shaft 118 through a sprocket chain or belt 120 drives the sprocket and ratchet wheel shaft 82.

The shaft 112 also drives the rotating cutting-off blade 104 through a sprocket chain 122, a variable speed drive 124, sprocket chain 126, gear 128, a change gear 130, and a gear 132 secured on a shaft 134 which carries a cutting blade.

The shaft 134 drives through connecting gears

a vertical shaft 136 and a horizontal shaft 138. The shaft 138 through a sprocket chain 140 and sprocket wheels drives a shaft 142 that carries the cam 98. The rear end of the shaft 138 through a chain of gears 144 and sprocket chain 146 drives the shaft 46 which carries the rotating wiper blade 42.

The grooved glue-applying roll 60 is driven from the shaft 112 through a sprocket chain 148 which drives a shaft 150. This shaft through a sprocket chain 152 drives a shaft 154 which through gears 156 drives the shaft of the glue-roll 60.

Also, the shaft 150 through a sprocket chain 158, a sprocket chain 160, a variable speed drive 162, drives the draw-rolls 26 for the lower web 18. The draw-rolls 28 for the upper web are driven through a belt or sprocket chain 164.

The variable speed drives 124 and 162 which may be of the Reeves type, enables the operator to relatively vary the feeding of the front and rear end portions of the webs so as to maintain them under proper tension without placing undue strain thereon.

By varying the operations of the cutting-off blade 104 and the transverse adhesive applying wiper blade 42, with relation to the speed of travel of the webs, bags of different widths as desired may be manufactured on the machine. Such variation in timing of these parts with relation to the feed of the web may be easily accomplished by changing the gear 130 through which said cutting blade and wiper blade are driven.

Different length bags may be manufactured by employing suitable width webs, and adjusting the folding and scoring devices for the further edges of the webs (viewing Figs. 1 and 2) to accommodate the different widths.

It will be apparent that my machine is simple in construction, capable of producing bags uniformly and expeditiously and may be easily and quickly adjusted for the manufacture of bags of different lengths and widths.

As will be evident to those skilled in the art, my invention permits various modifications without departing from the spirit thereof or the scope of the appended claims.

What I claim is:

1. In a bag machine of the class described, the combination of means for feeding two webs longitudinally one over the other, means for adhesively securing together longitudinal margins of the webs at one side of the longitudinal centers of the webs, means for folding over upon itself the other longitudinal margin of one of the webs, means for applying stripes of adhesive over the inner surface of said folded over margin and over the surface of the margin of the other web adjacent thereto, means for applying transverse stripes of adhesive to the inner surface of at least one of the webs, with the centers of the stripes of adhesive spaced apart corresponding to the width of the bags to be formed, means for positioning the webs together as they are being fed, and means for severing the webs through the centers of said transverse stripes of adhesive during the continued feeding of the webs.

2. A structure according to claim 1 in which means is provided for applying covering strips to the surfaces of said stripes of adhesive.

3. The combination of means for feeding a web longitudinally, means for applying a stripe of adhesive to one of the longitudinal margins of the web as it is being fed, and devices for apply-

ing a covering strip to the stripe of adhesive having provision of means for forming transverse loops in the covering strip spaced apart longitudinally of the covering strip.

5. The combination of means for feeding a web longitudinally and means for applying a stripe of adhesive to the web longitudinally thereof, devices for feeding a covering strip longitudinally over said stripe of adhesive comprising 10 a roller for applying the strip to the adhesive, means for rotating the roller at the same surface speed as the surface speed of the feed of the web, and means acting automatically at predetermined intervals during the feeding of the web 15 to retract the roller from the web and increase the strip-feeding action thereof and then restoring the roller in strip-applying engagement with the web and restoring its surface speed to the surface speed of the feeding of the web whereby 20 transverse loops are formed in the covering strip at spaced points.

5. The method of manufacturing bags of the class described which comprises feeding two webs longitudinally one over the other, adhesively securing together longitudinal margins of the webs at one side of the longitudinal centers of the webs as they are being fed, folding over upon itself the other margin of one of the webs, applying a stripe of adhesive over the inner surface of said 25 folded over margin and over the surface of the margin of the other web adjacent thereto, applying transverse stripes of adhesive to the inner surface of at least one of the webs with the centers of the stripes spaced apart corresponding 30 to the width of the bags to be formed, positioning the webs together as they are being fed, and severing the webs through the centers of 35 said transverse stripes of adhesive during the continued feeding of the webs.

40. 6. The combination of means for feeding a web longitudinally, means for applying a stripe of adhesive to the web longitudinally thereof as it is fed, devices for feeding a covering strip longitudinally over said stripe of adhesive comprising 45 a roller for applying the strip to the adhesive, means for rotating the roller at the same surface speed as the surface speed of the feed of the strip, means acting automatically at predetermined intervals during the feeding of the web 50 to retract the roller and the portion of the strip engaged by the roller from the web and at the end of a predetermined interval after each such retracting movement restoring the roller in strip-applying engagement with the web, and 55 means for increasing the speed of said roller during each period that it is thus retracted so as to cause spaced transverse loops to be formed in the strip.
